UNITED STATES PATENT OFFICE.

BARNES NEVILLE WALLIS, OF WESTMINSTER, LONDON, ENGLAND, ASSIGNOR TO AIRSHIP GUARANTEE COMPANY LIMITED, OF WESTMINSTER, ENGLAND, A BRITISH COMPANY.

AIRSHIP.

Application filed June 2, 1925, Serial No. 34,319, and in Great Britain June 12, 1924.

This invention relates to airships.

According to the present invention, instead of locating the main loads, such as the cars or coaches for the passengers and crew so that they are situated, or project outside the streamline of the airship, we locate them within the streamline or outer envelope thereof and thereby avoid the wind resistance offered by the projecting structures hitherto used. To this end the cars or coaches forming the said main loads may be suspended from one of the upper longitudinal girders, usually at the points where the said girder joins the transverse frames, and located symmetrically on each side of the airship within spaces formed between the outer envelope of the airship and the hydrogen gas bags. Communication may also be established between the nose and tail of the airship and the said cars or coaches by means of corridors disposed longitudinally of the airship and suspended on each side thereof between the outer envelope and the gas bags. Communication may also be established between the cars or coaches disposed respectively on each side of the airship or between the aforesaid longitudinally disposed corridors by means of transversely positioned staircases formed preferably within the transverse frames, the latter, to this end, being constituted by built-up space frame girders which are preferably triangular in cross section.

The hydrogen gas bags contiguous to the cars or coaches may be specially shaped to provide the requisite additional space taken up by the cars or coaches.

In order to avoid close contact between the hydrogen gas bags and the inside walls of the said cars or coaches which might give rise to an element of danger by reason of the close proximity of the gas and its possible escape into the quarters for the passengers and crew, we may cover the inside wall of the cars or coaches with a layer of material which is impervious or substantially impervious to hydrogen and we may also leave a substantial space between the said inside walls and the adjacent gas bags, (formed, for example, by a light girder-work structure projecting from the inside walls of the

cars or coaches), which space, or which girder-work structure, may also be enclosed by a layer of material which is impervious or substantially impervious to hydrogen. 55 Suitable means may also be provided for creating a current of air through said space so as to set up a circulation of fresh air therein which will effectually prevent the accumulation of any escaping gas that may enter said space. For this purpose we may provide at one end of the enclosed space a scoop, the open end of which may face the direction of travel of the airship so as to direct a current of fresh external air into said space when the airship is in motion. A similar scoop may be provided at or near the other or rearward end of said space and facing in the opposite direction to enable the current of air to leave said space and a 60 continuous flow of fresh air to take place. 65

In order that the said invention may be clearly understood and readily carried into effect the same will now be described more fully with reference to the accompanying drawing, which shows more or less diagrammatically one embodiment of the invention, and in which:—

Figure 1 is an elevation of an airship constructed according to the present invention. 80

Figure 2 is a sectional elevation of the cars or coaches on an enlarged scale, the outer wall or envelope being removed to show more clearly the internal structure of the said cars or coaches. 85

Figure 3 is a section on the line 3—3 of Figure 2, with the outer wall of the car or coach in position.

Figure 4 is a sectional plan view of the contiguous ends of two coaches showing 90 their disposition on each side of one of the transverse frames the section being taken on the roof level of the coaches.

Figure 5 is a diagrammatic elevation of the front part of the airship showing in 95 dotted lines the position of the coaches; the cables for suspending the same from one of the longitudinal girders, as also the ventilating scoops.

Figure 6 is a diagrammatic cross sectional view showing the symmetrical disposition of the coaches on each side of the airship; 100

their suspension means as also the space provided between the gas bags and the coaches for the circulation of air.

Figure 7 is a diagrammatic sectional view showing more clearly the ventilating passage located between the coaches and the gas bags.

Figure 8 is a diagrammatic sectional view of one of the coaches, showing the light girder-work structure which serves to separate the coaches from the contiguous gas bags, and

Figure 9 is a face view of part of Figure 8.

Figure 10 shows a modified arrangement in which the car or coaches are disposed low down within the streamline of the airship between the keel thereof and one of the gas bags and extending from side to side of the airship.

Figure 11 is a part sectional elevation of Figure 10, the outer cover of the airship being removed to show the interior of the cars or coaches.

Figure 12 is a longitudinal section of the front part of the airship showing the corridors by means of which access is obtained to the car or coaches shown at Figures 10 and 11.

Figure 13 is a diagrammatic plan view of the corridor shown at Figure 12, and

Figure 14 is a section showing the method of suspending the said corridors from the upper longitudinal frames.

A, A are the longitudinal frames; B, B are the transverse frames; C, C are the gas bags; D, D the outer envelope or streamline of the airship. The gas bags C, C, as shown at Figures 6 and 7, are specially shaped at

C¹ to provide the requisite additional space for the coaches or cars E, E, the latter being disposed symmetrically on each side of the airship within the space formed between the outer envelope D, D, and the gas bags C, C.

Four coaches E, E, are shown disposed in pairs on each side of the airship, each coach E being positioned between a pair of transverse frames B, B, and a pair of longitudinal girders A, A. Each coach, which has an upper deck e, and a lower deck e¹, is built

up of a light open metal framework, and is slung or suspended from one of the longitudinal girders A¹ by means of cables F, F, as shown more clearly at Figures 5, 6 and 8.

G (Figures 1, 2, 3 and 4) is a corridor one of which is provided on each side of the airship and which extends longitudinally from the nose to the tail thereof. The said corridor, which may be slung or suspended from

one of the longitudinal girders and located between gas bags and the outer cover or envelope D of the airship, is placed in communication with the interior of the coaches by means of staircases e², e². The coaches

are provided with windows e³, e³ and com-

munication is established between the upper deck e and the lower deck e¹ by staircases e⁴, e⁴. Additional staircases (not shown) may be provided for the purpose of establishing communication between the coaches on each side of the airship, and such staircases may be located within built-up transverse frames as described in our co-pending patent application No. 2116 of 1924. H is the space which is provided between the coaches E, E, and the gas bags C. h, h are the inlets to said space H, and h¹, h¹, are the outlets; it will be understood that the said space extends the whole length of said coaches. I (Figures 8 and 9) is the light structural framework attached to the top, inner wall, and bottom of the coaches, and it is covered by a layer J of a material which is impervious or relatively impervious to hydrogen, a similar layer of material being preferably also located around the coaches at J¹ (Figures 3 and 8). The mesh wiring K which surrounds the gas bags is attached at I¹, I¹, to the framework I.

Referring to Figures 10 to 14 it will be observed that in this embodiment of the invention the car or coaches for the passengers and crew are located low down in the airship between one of the gas bags and the keel of the ship, the coaches extending from side to side of the airship and being disposed between contiguous transverse frames K', K' (Figure 11). Any desired number of floors may be provided three being shown by way of example namely, the lower floor L, a middle floor L¹ and a top floor L²; an additional floor L³, indicated in dotted lines on the right hand side of Figure 10, may also be provided on each side of the airship. The coaches as before are suspended from the longitudinal frames by suspension wires M, M, one method of suspension being shown on the right hand side of Figure 10 and an alternative suspension system being shown on the left hand side of the same figure. The windows N, N, as before are formed in the outer cover and access to the different floors is obtained by means of staircases O, O. The coaches as before are also separated from the gas bag located above the same by means of a light girder-work structure P and the coaches, as also the said girder-work structure P may be lined with a material which is impermeable or relatively impermeable to hydrogen. In this embodiment of the invention access to the coaches is obtained by means of a pair of corridors Q, Q¹ located centrally of the ship towards the keel thereof and extending from the nose of the airship to the entrance R to the said coaches. The said corridors are suspended from the upper transverse frames by means of suspension wires R², R² and a light girder-work structure or the like R¹ is provided for the purpose of separating the gas bags from

the said corridors, the gas bags themselves being adapted to straddle the said corridors and the girder-work structure R¹ disposed around the same. Two corridors are preferably provided as shown one corridor Q¹ being used as an entrance to the coaches and the corridor Q¹ being employed as an exit therefrom.

What I claim and desire to secure by Letters Patent of the United States is:—

1. An airship comprising gas bags, an outer envelope surrounding said gas bags, coaches disposed between said gas bags and said outer cover and means separating said coaches from said gas bags so as to leave an air space between the gas bags and the inner walls of said coaches.

2. An airship as claimed in claim 1, in which means are provided for promoting a circulation of air within the space left between the inner walls of the coaches and the gas bags.

3. An airship comprising gas bags, an outer envelope surrounding said gas bags, coaches disposed between said gas bags and said outer cover, and a light girderwork structure spacing apart said coaches from said gas bags.

4. An airship comprising gas bags, an outer cover surrounding said gas bags, coaches disposed between said gas bags, and said outer cover, means spacing apart said coaches from said gas bags, and means for promoting a circulation of air within the space left between the gas bags and the inner walls of the coaches.

5. An airship as claimed in claim 3 in

which the light girderwork structure is covered with a material which is impervious or substantially impervious to hydrogen.

6. An airship comprising gas bags, an outer envelope surrounding said gas bags, coaches disposed between said gas bags and said outer cover, a covering material for the inside walls of said coaches, said material being impervious or relatively impervious to hydrogen, and means spacing apart said coaches from said gas bags.

7. An airship comprising gas bags, an outer envelope surrounding said gas bags, coaches disposed between said gas bags and said outer cover, a material impervious or relatively impervious to hydrogen surrounding the inner walls of said coaches, a light girderwork structure spacing apart said coaches from said gas bags, and a covering material for said light girderwork structure, said material being impervious or relatively impervious to hydrogen.

8. An airship comprising transverse frames constituted by built-up space frame girders, gas bags, an outer cover surrounding said gas bags, coaches disposed between said gas bags and said outer cover, and staircases in said transverse frames for establishing communication between said coaches.

9. An airship comprising a rigid framework, gas bags disposed within said rigid framework, an outer cover surrounding said gas bags, coaches disposed between said gas bags and said outer cover, and means for suspending said coaches from said rigid framework.

BARNES NEVILLE WALLIS.
